(57) **CLAIM**

The ornamental design for a golf club shaft, as shown and described.

DESCRIPTION

FIG. 1 is a front perspective view of a golf club shaft embodying our new design.

FIG. 2 is an enlarged front elevational view of the golf club shaft, the broken away section being shown for ease of illustration.

FIG. 3 is a top end view of the golf club shaft.

FIG. 4 is a bottom end view of the golf club shaft.

FIG. 5 is a front perspective view of an alternate embodiment golf club shaft embodying our new design.

FIG. 6 is an enlarged front elevational view of the alternate embodiment golf club shaft, the broken away section being shown for ease of illustration.

FIG. 7 is a top end view of the alternate embodiment golf club shaft; and,

FIG. 8 is a bottom end view of the alternate embodiment golf club shaft.

The broken lines in the figures are for illustrative purposes only and form no part of the claimed design.
